JEWEL OLIVING MACHINE

Harry Dewey Weaver, Lancaster Township, Lancaster County, Pa., assignor to Hamilton Watch Company, Lancaster, Pa.

Application October 1, 1942, Serial No. 460,395

3 Claims. (Cl. 51—58)

This invention is directed to improvements in apparatus for oliving jewels such as used in the watchmaking industry.

While the invention is mainly intended for that step in the processing of watch jewels known as oliving, it is capable of being utilized wherever there is need of internal grinding, polishing, reaming or finishing of small parts either jewels or metallic.

The term oliving refers to the rounding of the internal edges of the bore of watch jewels to reduce the friction between the jewel and the shaft mounted therein.

The oliving of jewels for use in watches is becoming increasingly difficult. The demand for smaller and smaller movements without any sacrifice of accuracy makes it necessary to reduce the size of the jewels used. Watch jewels are made of synthetic rubies or sapphires and are extremely hard. Only diamond dust may be successfully used in cutting them, for while "carborundum" is harder and will cut the jewels, yet the property of the diamond of splitting and always presenting a sharp edge makes this the only practical material to use. The problem of cost is of course important. The use of excessive amounts of this dust would materially increase the cost of production. An apparatus, therefore, which uses only a small amount of diamond dust and allows practically no waste is necessary. There is also the time element to be considered. In boring a jewel, which may be done by a battery of machines attended by a single operator each boring operation takes between eight and fifteen minutes, depending on the size of the jewel. The oliving which must have manual manipulation during the operation takes a proportional time. The oliving machine must therefore overcome the time element in order to be practical. As watches are of many sizes and each individual watch has different size jewels, this machine must also be adjustable to accommodate many different sizes. The apparatus of the present invention is designed to meet and surmount these difficulties which are present with machines now in use.

The object of this invention is to provide an apparatus which will rapidly and accurately olive the jewel.

A further object is to provide a jewel oliving apparatus which can be adjusted to different size jewels.

A further object is to provide a jewel oliving apparatus which is economical in use of cutting material.

A further object is to provide a jewel oliving apparatus which will perform the necessary operation in a minimum of time.

A still further object is to provide an apparatus which may be used in the enlarging, ream-

ing, grinding or polishing of the bore of small parts.

The invention is illustrated in the accompanying drawings, in which:

Fig. 1 is a side elevation of the oliving machine with a jewel shown with the wire but without the bow.

Fig. 2 is a top plan of the machine.

Fig. 3 is a front view of the bow with several jewels strung on the bow wire.

Fig. 4 is an end view partly in section showing the bow in oliving positions and with the dust carrying post removed.

Fig. 5 is a section of the jewel before and after oliving.

The oliving apparatus comprises a base 11 upon which a stationary unit carrying the driving wheel and one driven wheel and a movable unit carrying the second driven wheel are mounted.

Standards 12 and 13 carry in appropriate bearings a driving shaft 14 upon which is carried a centrally mounted driven wheel 15. This wheel

15 is formed of "Lucite," hard rubber, hard leather or a like material having a fairly high coefficient of friction as its driving contact is frictional. Mounted also on shaft 14 and secured thereto by set screws (not shown) are pulleys 16 and 17, pulley 16 being smaller than 17 to give variation in speed if needed. The shaft

30 is journaled in "nylon" high speed bearings 18 (Fig. 4) which have an oil feed through oil cups 19 mounted on bearing sleeves 20. These sleeves

20 set at their inner ends 21, in recesses 22 to prevent the diamond dust from contacting the

35 bearing. Guards 23 carried outwardly on the ends of the sleeves also serve to prevent the entrance of the diamond dust to the shaft bearings. Set screws 24 permit easy removal and replacement of the bearings after wear has rendered them useless.

The shaft 14 is driven at a high rate of speed, upwards of 2200 revolutions per minute through either of the pulleys 16 or 17 by a twisted raw hide belt 25 which is driven in turn by a motor 45 through a series of step up pulleys (which is not shown, being no part of the invention). While the mechanism for producing the high speed is no part of the invention, the resultant

50 high speed is essential. It is this high speed that allows the jewel to be olived in from ten to thirty seconds. It is this rapid oliving that makes it practical to use such a machine in production work, as every jewel must be individually olived.

55 The standards 12 and 13 are formed with extensions 26 which have journaled therein a shaft 27. Mounted on said shaft is a frame 28. This frame carries an upper shaft 29 upon which a yoke 30 having arms 31 is pivotally carried. Projecting outward and at right angles to said

frame is a footpiece 32 having a set screw 22 threaded thereinto.

The arms 31 which through yoke 30 are pivoted at one end to the upper shaft 29 carry a shaft 34 at their outer ends. This shaft supports a jewel receiving wheel 35 and spacer blocks 36 at a position above the central wheel 15. The wheel 35 has a peripheral groove 37 formed therein for receiving the jewel. A spring 38 tends to swing the arms 31 about the shaft 29 inward toward the central driving wheel which forces the wheel 35 against said driving wheel with sufficient pressure to assure transfer of rotation between said wheels.

A lower spring 39 engages the frame 28 and an anchor plate 40 secured to the base 11. This forces the set screw 33 in the foot plate 32 securely against the contact plate 41 also on the base 11. Movement of this set screw against the plate 41 swings the frame about the shaft 27 and provides adjustment for different size jewels. A locking screw 42 is threaded into the foot piece and engages the set screw 33 to securely hold it and prevent the slightest movement in the adjustment.

A sliding base 43 is mounted for sliding movement through an upstanding ridge 44 on base 11 and a slot 45 in said sliding base. A set screw 46 provides the adjustment of said base to align the jewel receiving wheels. Bolts 47 securely hold this base in adjusted position.

Similar to frame 28 a frame 48 is journaled on a shaft 49 carried in upstanding ears 50 on base 43. A yoke 51 similar to yoke 30 is pivotally carried by shaft 52 journaled in the upper part of frame 47. This yoke has arms 53 which support a shaft 54 carrying a jewel receiving wheel 55 formed identical with jewel wheel 35. A spring 56 forces the jewel wheel 54 into contact with central driving wheel 15 while a second lower spring 57 urges the frame against the action of a set screw 58 similar in operation to set screw 33. This provides adjustment of the pair of jewel wheels to regulate the distance the one from the other while the upper springs insure contact of said jewel wheels with the central driving wheel. These jewel wheels may be swung upward and over to allow access to the central driving shaft and wheel 15.

The hand tool or bow 59 on which the jewels are held is shown in Fig. 3 with a single jewel 60 ready for oliving and a number of others 61 strung on the wire 62 which is formed of a cross section very little smaller than the bore of the jewel. The bow is formed of spring wire ending in swivel connections on a bolt 63. The wire 62 is securely clamped by this bolt which is turned snugly enough by hand.

A post 64 is removably positioned in hole 65 in base 11. This post supports on a level slightly above the top of the jewel driving wheels a shelf 66 secured to the post by a bolt 67. The shelf carries a small quantity of the oliving compound 68 of olive oil and diamond dust and has an upstanding projection 69 formed with a sharp edge 70 used in separating the jewels strung on the wire.

The jewels illustrated in Fig. 5 show the product before and after oliving. Jewel 71 is the finished jewel except for oliving and shows the straight side 72 of the jewel bore. Jewel 73 which is the finished olived jewel shows the rounded side 74 of the bore. This oliving process as can be readily seen reduces the contact of the

shaft with the jewel bearing, thus reducing the friction. It is, of course, necessary to use an end bearing to take care of thrust and this must be done with every olived jewel.

5 In operation, assuming the belt to be driven and the central driving wheel turning at approximately 2200 R. P. M., the alignment of the sliding base and the adjustment of the set screws 33 and 58 for the correct size to be made, the jewel receiving wheels 35 and 55 are turning approximately 4500 R. P. M. The jewels to be olived, all of the same size are strung on the wire which is, of course, withdrawn from the bolt for stringing and the wire reinserted in the bolt after stringing, drawn taut against the spring action of the bow and secured. These jewels which may be of almost any number or only one are ready for oliving.

20 The operator, sitting directly in front of the machine, in line with the jewel receiving wheels dips the wire at a central point into the paste formed of diamond dust and oil. This wire which is of soft copper retains the paste and a single jewel is slid along the wire by means of 25 the projection edge 70, the jewels being too small to be separated by the fingers, to a point on the wire covered with paste. The jewel is then brought into contact with the jewel receiving wheels and in the peripheral grooves of these 30 wheels, as shown in Figs. 1 and 4.

The jewel is frictionally driven by the jewel receiving wheels at a high rate of speed, upwards of 20,000 R. P. M. the bow being rocked a predetermined number of times to round the side of the bore in said jewel. This operation, because of the high speed, is completed in a few seconds varying from eight to thirty, depending on the size of the jewel. When it is considered that normally the oliving operation took from four to 40 ten minutes, the practicability of this machine is demonstrated.

The use of olived jewels in a watch in replacement of the usual straight bore jewel reduces the friction and allows finer and more accurate adjustment which means closer timekeeping.

What I claim is:

1. An apparatus for oliving jewels comprising a base, a motor driven wheel rotatively mounted on said base, a pair of driven wheels, each formed with a jewel retaining peripheral groove, a bow wire for axially supporting a number of jewels, said bow being manually positioned to bring successive jewels into wheel contacting position.

50 2. An apparatus for oliving jewels having a central bore comprising a base, a motor driven wheel rotatively mounted on said base, a pair of driven wheels, each formed with a jewel retaining peripheral groove, a bow, a bow wire for axially supporting a number of jewels formed with center holes, said bow being manually operated to bring any of said jewels to wheel contacting position and abrading means applied to said bow wire to abrade and polish said center jewel hole.

60 3. An apparatus for oliving watch jewels having a central bore therein comprising an abrading wire for supporting a plurality of said jewels, a rotating member, and manually operable means for controlling the line of contact between said abrading wire supporting means and said jewel when in contact with said rotating member.
